Attorneys

UNITED STATES PATENT OFFICE.

HERMAN R. ISLER, OF NORWOOD, OHIO, ASSIGNEE TO THE OAKLEY MACHINE TOOL COMPANY, OF CINCINNATI, OHIO, A CORPORATION OF OHIO.

TOOTH-REST.

1,249,630.

Specification of Letters Patent. Patented Dec. 11, 1917.

Application filed January 26, 1917. Serial No. 144,756.

To all whom it may concern:

Be it known that I, HERMAN R. ISLER, a citizen of the United States, and a resident of Norwood, in the county of Hamilton and 5 State of Ohio, have invented certain new and useful Improvements in Tooth-Rests, of which the following is a full, clear, and exact description, reference being had to the accompanying drawings, forming a part 10 of this specification.

My invention relates to tooth-rests whereby the successive teeth of a cutter may be so positioned with reference to a grinding wheel that the same may be uniformly 15 ground.

The objects of my invention are first, to provide a tooth-rest of the character mentioned, having a non-resilient or rigid blade adapted to serve as a rest for the successive 20 teeth of a cutter and so mounted upon a resilient support as to permit the free rotation of the cutter to bring the successive teeth in position on said blade; second, to provide a device of such description of simple, inexpensive and efficient construction. 25

Other objects of my invention will be apparent to those skilled in the art to which the same appertains, from the following description thereof, taken in connection with 30 the accompanying drawings.

In the drawings:

Figure 1 is a central vertical section of my new tooth-rest, parts being shown in elevation.

Fig. 2 is a front elevation of said invention, a portion being broken away to show the resilient mounting for the blade.

Fig. 3 is a plan of said tooth-rest.

Fig. 4 is a side view of the end of a modified form of the tooth rest.

The numeral 1 indicates an arm, the said arm being arranged to be supported in any suitable manner upon the bed or other portion of a grinding machine, the said arm 1 being arranged, as will be understood, to move in various directions in accordance with the construction heretofore in use. Adjustably mounted in an aperture in the head 2 of the arm 1 is a second arm 3, the 45 axis of said arm 3 being vertical to the axis of the arm 1. A set screw 4 secures the arm 3 in any desired position.

The arm 3 is bored as clearly shown in Fig. 1 of the drawings, the upper portion of

said bore being of larger diameter than the 55 lower portion thereof.

The numeral 5 indicates the resilient support for the rigid blade of my tooth-rest. The said support is of generally cylindrical form, but is provided with an intermediate 60 portion 6 which is suitably shaped and tempered to give the required resilience to the support 5. One end of said support is secured by a rivet 7 in the small bore at the lower end of the arm 3, and the said support is so shaped, during the forming of the resilient portion 6, that the upper end thereof inclines toward one side of the larger bore at the upper end of said arm 3. The free end of the support 5 in the form of the 70 device illustrated, is provided with a head 8 which has a transverse threaded perforation for a screw 9 by means of which the rigid blade 10 of the device is secured to the support, but it will be understood that said 75 end may itself be extended and shaped to form the rigid blade as illustrated in Fig. 4 of the drawings. The upper end of the arm 3 is provided with guides 11 between which the lower portion of the head 8 of the support reciprocates; the said guides being provided to prevent lateral motion of the head 8 and thereby of the blade 10.

From the foregoing description, the nature and spirit of my invention will be apparent to those skilled in the art, and the various modifications within the scope of 85 said invention wherein the principles thereof may be embodied, will be readily suggested.

Having thus described my invention, what 90 I claim as new and desire to secure by Letters Patent is:

1. A tooth-rest comprising a member, said member being formed with a thinner resilient portion intermediate its ends and an 95 end adapted to serve as a tooth-rest, and means for adjustably mounting said support on a machine tool.

2. A tooth-rest comprising an arm, means for adjustably mounting said arm on a machine tool, and a member mounted in said arm, said member being formed with a thinner resilient portion intermediate its ends and an end adapted to serve as a tooth-rest. 100

3. A tooth-rest comprising an arm, means for adjustably mounting said arm on a machine tool, a member mounted in said arm, said member being formed with a thinner 105

resilient portion intermediate its ends and an end adapted to serve as a tooth-rest, and guides arranged to secure said member against lateral movement.

5. A tooth-rest comprising an arm, means for adjustably mounting said arm on a machine tool, said arm being bored, a member, said member being formed with a resilient portion intermediate its ends and an end 10 adapted to serve as a tooth-rest, one end of said member being secured in the bore in the lower portion of said arm, and the upper portion of said member being arranged to move in the upper portion of said bore.

15. 5. A tooth-rest comprising an arm, means for adjustably mounting said arm on a machine tool, said arm being bored, a member, said member being provided with a resilient portion intermediate its ends and an end 20 adapted to serve as a tooth-rest, one end of said member being secured in the bore in the lower portion of said arm, and the upper portion of said member being arranged to move in the upper portion of said bore, and 25 guides arranged to secure said member against lateral movement.

6. A tooth-rest comprising a supporting member, a cut away resilient portion intermediate its ends, a blade secured to said 30 support and means for adjustably mounting said support on a machine tool.

7. A tooth rest comprising an arm, means for adjustably mounting said arm on a machine tool, a support mounted in said arm,

said support being formed with a thinner 35 resilient portion intermediate its ends, and a blade secured to the free end of said support.

8. A tooth-rest comprising an arm, means for adjustably mounting said arm on a machine tool, a resilient support mounted in 40 said arm, a blade secured to said support, and guides arranged to secure said support and blade against lateral movement.

9. A tooth-rest comprising an arm, means 45 for adjustably mounting said arm on a machine tool, said arm being bored, a support, said support being provided with a resilient portion intermediate its ends, one end of 50 said support being secured in the bore in the lower portion of said arm, and the upper portion of said support being arranged to move in the upper portion of said bore and a blade secured to the free end of said arm.

10. A tooth-rest comprising an arm, means 55 for adjustably mounting said arm on a machine tool, said arm being bored, a support, said support being provided with a resilient portion intermediate its ends, one end of 60 said support being secured in the bore in the lower portion of said arm, and the upper portion of said support being arranged to move in the upper portion of said bore, a blade secured to the free end of said arm, and guides arranged to secure said support 65 and blade against lateral movement.

HERMAN R. ISLER.
